UNITED STATES PATENT OFFICE.

CHARLES W. TRULOCK, OF LOS ANGELES, CALIFORNIA.

INCANDESCENT-LAMP LOCK.

992,084.

Specification of Letters Patent. Patented May 9, 1911.

Application filed June 30, 1909. Serial No. 505,162.

To all whom it may concern:

Be it known that I, CHARLES W. TRULOCK, a citizen of the United States, residing at Los Angeles, in the county of Los Angeles and State of California, have invented certain new and useful Improvements in Incandescent-Lamp Locks; of which the following is a specification.

My invention relates to incandescent lamp locks, and has for its object to provide means to prevent the removal of an incandescent lamp from the lamp socket without a proper key, thereby positively preventing parties from removing the lamp and inserting a larger one or connecting electric devices, such as heaters, cookers, curling irons, and the like with the lamp socket, hence guarding against the utilization of an excessive amount of electric current.

20 A further object of the invention is to provide a combination plug and socket member so constructed that the plug end thereof will fit into any standard screw threaded lamp socket and the socket end receive any 25 standard size and make of incandescent lamp having a screw threaded base.

20 A further object is to provide a removable plug socket so that a lamp may be connected to the lamp socket proper if so desired.

30 A still further object is to provide a plug socket having a swivel connection between the plug end thereof and the socket end, so that the socket end will be free to revolve with the lamp when the plug socket is locked 35 in position in the incandescent lamp socket proper.

40 A still further object is to provide a collar or shell which is adapted to conceal the plug socket and prevent its removal or the removal of the incandescent lamp without the use of a key.

45 With these and other objects in view, the invention consists in the construction and novel combination and arrangement of parts hereinafter fully described, illustrated in the accompanying drawings, and pointed out in the claims hereto appended.

50 I am aware that various changes such as in the form, proportions, size and other minor details of construction herein shown and described as an embodiment of my invention may be made without departing from the spirit or scope of the invention or sacrificing any of the advantages thereof, 55 and I therefore reserve the right to make

any such changes as fairly fall within the scope of the same.

Referring to the accompanying drawings forming a part of this specification wherein like characters of reference denote similar parts throughout the several views: Figure 1, is an assembled view of the parts involved in the operation of my invention, the plug socket and collar being shown in longitudinal section, while the standard screw threaded lamp socket is shown only partly in section. Fig. 2, is a longitudinal section of the combined swivel plug socket. Fig. 3, is a detail showing the location of the means for holding the socket of the swivel adapter stationary for removing the lamp therefrom. Fig. 4, is a view in cross-section taken on line Z—Z of Fig. 3. Fig. 5, is a view in cross-section taken on line X—X of Fig. 3. Fig. 6, is a view of the key employed for releasing the lamp from the socket of the plug socket. Fig. 7, is an assembled view of a modification of my invention. Fig. 8, is an extended view of the parts involved in the operation of the invention, the plug socket 75 being shown in longitudinal section, the collar employed to conceal and lock the lamp in the socket portion being removed. Fig. 9, is a view in cross-section taken on line X—X of Fig. 7. Fig. 10, is a detail showing the lower end of the dog for locking the plug socket in the standard screw threaded lamp socket and the key holes in the collar and plug socket. Fig. 11, is a view in cross-section also taken on line X—X of Fig. 7, with 80 the exception that the key is shown as having released the dog from connection with the standard screw threaded lamp socket. Fig. 12, is a perspective view of the locking dog. Fig. 13, is a view of the key for releasing the locking dog from engagement with the lamp socket. 85

I will now fully describe the preferred form of my invention, and in carrying out the aim thereof I have illustrated in Fig. 1, 100 of the drawings an ordinary standard lamp switch socket 1, having the usual screw threaded socket or lamp receiving shell 2 into which the plug end 3 of the swivel plug socket A is adapted to enter. The swivel 105 plug socket A it will be observed consists of the plug 3 having its upper portion screw threaded as at 4. The plug 3 is provided with the usual center contact button or terminal 5 adapted to engage with the con- 110

tact button or terminal 6 in the receiving shell or socket 2, as clearly shown in Fig. 1. Adapted to enter the screw threaded plug 3, is a lamp receiving shell or socket 7, which 5 is provided with the screw threads 8. The upper end of this screw threaded shell or socket 7 is also provided with a contact button or terminal 9 adapted to engage the contact button or terminal 10 at the upper end 10 of the incandescent lamp 11, as clearly shown in Fig. 1. This contact button or terminal 9, it will be observed passes upwardly through the insulated head 12 of the screw threaded shell or socket 7 and is provided with a pocket 13, which pocket is adapted to receive the headed end 14 of the stem 15 which extends downwardly from the contact button or terminal 5 at the upper end of the screw threaded plug 3. By this 20 arrangement it will be readily seen that I provide a swivel connection between screw threaded plug 3 and screw threaded socket 7, which enables the screw threaded socket 7 to freely turn or revolve should anyone 25 endeavor to remove the lamp 11 therefrom without first holding the socket stationary. The means for holding the screw threaded socket 7 stationary will be fully described hereinafter.

30 In order to conceal the swivel plug socket and prevent the removal of lamps without a proper key, I employ a collar or shell 16, which collar is provided with the upper bead 17 and the lower bead 18. The upper 35 portion of the collar is also provided with a plurality of snaps 18' which are concaved after being slit on opposite sides as at 19. These snaps 18' it will be observed, snap over the bead 20 of the standard lamp socket 40 so that it brings the bead 17 of the collar 16 in engagement with the lower face of bead 20 to prevent the collar 16 from working up any higher on the socket 1. Secured to the collar upon the inside thereof adjacent the 45 lug 21 of the screw threaded swivel socket 7, when the parts are assembled as shown in Fig. 1, by means of suitable fastening means 22 is a spring member 23, which is provided at its free end with a fiber lug 24 as clearly 50 shown in Figs. 3, 4, and 5. This member 23 is made of spring brass or other suitable material and is adapted to lay close enough to the collar when the parts are assembled so as not to allow the lugs 21 to engage the 55 fiber lug 24, should anyone turn the lamp in trying to remove it. By this arrangement it will be readily seen that the screw threaded socket 7 and lamp 11 are free to turn and still the lamp cannot be removed 60 without first inserting the key 25 into the key hole 26 which is partly in the collar and partly in the swivel member 27; after the key 25 has been inserted in the key hole 26, it is turned to the right and the lip 26 engages the back of the spring member near 65 it, free end thereof and forces and holds the fiber lug 24 in engagement with the outer face of the screw threaded socket 7. After this has been done the lamp is turned until one of the lugs 21 strikes and engages the fiber lug 24 of spring member 23 which holds the screw threaded socket 7 stationary and allows the lamp 11 to be easily removed. The screw threaded socket 7 it will be understood must be held stationary when either 70 removing a lamp or inserting one, otherwise the lamp cannot be removed or inserted owing to the turning of the screw threaded socket 7 at the swivel joint. The lower end of the collar 16 is provided with an insulated ring 27 of hard material which prevents the lock from being picked or otherwise tampered with from the lower end. It will be observed that the collar 16 cannot be removed until after the lamp 11 has been 85 detached from the screw threaded socket 7, nor can the swivel plug socket be removed from the lamp socket until the collar is removed.

Referring to the modification of my invention shown in Figs. 7 to 13 inclusive, the reference character 28 designates an ordinary standard lamp switch socket, having the usual threaded socket or lamp receiving shell 29, which is provided with the usual 90 cutaway portion 30, and into which socket the upper end 31 of the removal plug socket B is adapted to enter. The removable plug socket, it will be observed consists of the plug portion 31, which is provided with the 95 screw threads 32. The upper end of this screw threaded plug 31 is provided with the usual center contact button or terminal 33 adapted to engage with the contact button or terminal 34 in the receiving shell 29. Secured to the lower end of the screw threaded plug 31 or integral therewith is a shell 35 which is adapted to receive the screw threaded lamp receiving shell or socket 36. The upper end of this screw threaded shell or 100 socket 36 is also provided with a contact button or terminal 37, adapted to engage the contact button or terminal 38 at the upper end of the screw threaded base portion of the incandescent lamp 39, as clearly shown in 105 Fig. 7. It will be observed that the contact buttons or terminals 33 and 37 are connected by means of the wire member 40. The screw threaded plug 31 is provided upon the inside 110 near the head thereof, with an insulated wall 41, having an opening 42 through which the wire member 40 is adapted to pass. To this wall 41 is pivotally connected by means of a pin 43, a dog member 44 having a nose 45 and the downwardly extending arm or stem 46. 115 This nose 45 it will be observed from Fig. 9 is adapted to pass through the slotted opening 47 in the wall of the screw threaded plug 31 and the opening or cutaway portion 30 in the wall or the receiving shell 29. The 120 125 130

spring wire member 48 which has one end curled around the arm or stem 46 of the dog 44 and the remainder thereof in engagement with the inner face of the screw threaded plug 31, holds the nose of the dog in this position until it is changed by means of the key 49 having the V-shaped end 50 and the shoulder 51. By inserting this key 49 into the aligned key hole openings 52 in the collar hereinafter more fully described and the screw threaded plug 31, as clearly shown in Fig. 10, it will be observed that the V-shaped end of the key 49 engages two faces of the arm or stem 46, as shown in Fig. 11. As this key is forced inward, it withdraws the nose 45 of the dog 44 from the openings 47 and 30, as clearly shown in Fig. 11.

When the dog 44 is in its locked position as shown in Fig. 9, the one edge of the nose 45 it will be observed is adapted to engage the edge 53 of the receiving shell 29 thereby preventing the removal of the plug socket B from the receiving shell 29 without the use of the key 49. The screw threaded plug 31 is provided with the guide 54, as clearly shown in Figs. 9, 10 and 11 to provide a guide for the key 49. The lower end of the screw threaded plug 31 of the plug socket B is provided with a spring wire member 54' so formed as to provide a pair of oppositely disposed depending arms 55 having their ends bent inwardly toward each other as at 56 and preferably tapered so as to provide a pointed end. These bent ends 56 are adapted to pass through the oppositely disposed openings 57 in the wall of the shells 35 and 36 when the collar 58, which is provided with the insulated shell 59 is slid down over the lower end 35 of the plug socket B and the extremities of the ends 56 are adapted to force themselves into the soft metal of the screw threaded base 59 of the lamps 39 thereby preventing their removal until the collar 58 has been removed, which is impossible until the dog 44 has been released from engagement with the receiving shell 29.

To assemble the several parts of my modified lamp lock, the upper threaded base 59 of the incandescent lamp 39 is first screwed into the receiving shell or socket 36 of the plug socket B. Then the key 49 is inserted into the key holes 52 and the key turned so that the shoulder 51 will engage the wall of the plug which holds the key in position without having to hold it in this position by means of the fingers. When this has been done the operator screws the threaded plug portion 31 of the plug socket B into the receiving shell or socket 29 of the switch socket 28; the operator then releases and withdraws the key which allows the dog 44 to resume the position shown in Fig. 9, which locks the same in position and prevents the removal of the plug socket B without again inserting the key 49.

When it is desired to remove the lamp 39 for any cause, the key 49 is inserted, the dog released from the shell 29, the plug uncured from the shell and the collar removed from the plug socket, which allows the arms 70 to spring outward and the lamp 39 removed from the shell or socket 29.

What I claim is:—

1. An incandescent lamp lock comprising a swivel plug socket consisting of a plug member and a socket member each having a central terminal, lugs carried by said socket member, said plug member being adapted to be connected with a lamp socket, an incandescent lamp adapted to be connected with said socket member, a collar having connection at one end with said lamp socket and adapted to conceal said adapter, and means carried by said collar adapted to be actuated by a key to engage one of said lugs to hold 85 said socket member stationary to enable the connection with or removal of the incandescent lamp socket from said socket member.

2. In combination with a screw threaded 90 incandescent lamp socket, a combined plug socket comprising a hollow screw threaded plug member, adapted to be connected with said lamp socket, a screw threaded socket member rotatably carried within said plug member adapted to carry an incandescent lamp, a collar removably connected with said lamp socket and inclosing said plug socket, and means for holding said rotatable socket member stationary for removing the 100 lamp therefrom.

3. A plug socket member comprising a hollow screw threaded plug member having a central terminal, and a screw threaded socket member rotatably carried within said plug member having a central terminal adapted to receive the screw threaded base of an incandescent lamp.

4. The combination with a screw threaded incandescent lamp socket, a plug socket consisting of two screw threaded shells one rotatable within the other, one of which is adapted to receive a screw threaded incandescent lamp, a sleeve connected with said lamp socket and concealing said plug socket, said sleeve having a key hole for the insertion of a key to engage and hold said rotatable shell stationary for the purpose of connecting or disconnecting a lamp therewith.

5. A combination electric plug and socket comprising a screw threaded plug member having a central terminal; and a screw threaded socket member having a central terminal, said socket member being partly concealed within said screw threaded plug member and rotatably carried thereby.

6. A plug socket comprising a hollow cylindrical screw threaded plug member having a central terminal at its upper end, a cylindrical screw threaded socket member 130

1 having a central terminal at its upper end carried partly within said cylindrical screw threaded plug member, and means for connecting said plug member and said socket member so as to leave each member free to be rotated independent of the other.

7. The combination of a hollow screw threaded plug member having a central terminal, a hollow screw threaded socket member having a central terminal, the upper end of which is concealed in said hollow screw threaded plug member, and means connecting with said terminals to allow either the plug member or the socket member to be rotated independent of the other.

8. In combination with a screw threaded incandescent lamp socket, an incandescent lamp lock comprising a hollow screw threaded plug member having a central terminal, a hollow screw threaded socket member having a central terminal, a swivel member connecting with said central terminals, a sleeve removably connected with said incandescent lamp socket for concealing said plug member and said socket member, and a spring arm secured to the inner face of said sleeve, said spring arm being actuated by means of a key so as to cause said spring arm to engage said socket member and hold the same stationary to enable the removal of an incandescent lamp therefrom.

9. In combination with an incandescent lamp socket, of an incandescent lamp lock comprising a screw threaded plug member having a central terminal adapted to fit into the receiving shell of said incandescent lamp socket, a screw threaded socket mem-

ber having a central terminal rotatably carried by means of said screw threaded plug member and adapted to receive the screw threaded base of an incandescent lamp, a one piece open ended cylindrical sleeve removably connected with said incandescent lamp socket adapted to inclose said screw threaded plug and said screw threaded socket, and means adapted to be actuated by means of a key for holding said rotatably screw threaded socket member stationary for the purpose of inserting or removing an incandescent lamp therefrom.

10. In combination with a screw threaded incandescent lamp socket, of an incandescent lamp lock comprising a plug socket consisting of a screw threaded plug member having a central terminal, a screw threaded socket member having a central terminal carried partly within said plug member adapted to receive the screw threaded base of an incandescent lamp, a swivel connection between said central terminals to allow the socket member to rotate independent of the plug member, a one piece cylindrical sleeve removably connected with said incandescent lamp socket having a swivel key-hole, and a fiber ring connected with the lower end of said cylindrical sleeve.

In testimony whereof I have hereunto signed my name to the specification, in the presence of two subscribing witnesses.

CHARLES W. TRULOCK.
